CLAIM

I claim the ornamental design for a multiplayer game machine, as shown and described.

DESCRIPTION

FIG. 1 is a front perspective view of a multiplayer game machine showing our new design;

FIG. 2 is a front view of the multiplayer game machine design shown in FIG. 1;

FIG. 3 is a back view of the multiplayer game machine design shown in FIG. 1;

FIG. 4 is a right view of the multiplayer game machine design shown in FIG. 1;

FIG. 5 is a left view of the multiplayer game machine design shown in FIG. 1; and,

FIG. 6 is a top view of the multiplayer game machine shown in FIG. 1.

The broken lines illustrate unclaimed environmental features and form no part of the claimed design.
